UNITED STATES PATENT OFFICE.

ESTILL B. BROWN, OF NEW YORK, N. Y.

DESIGN FOR A LAMP-SHADE.

44,703.

Specification for Design.

Patented Sept. 30, 1913.

Application filed August 9, 1913. Serial No. 783,944. Term of patent 7 years.

To all whom it may concern:

Be it known that I, ESTILL B. BROWN, a citizen of the United States, residing at New York city, in the county of New York, the State of New York, have invented a new, original, and ornamental Design for Lamp-Shades, of which the following is a specification, reference being had to the accompanying drawing, forming part thereof.

a top plan view of a lamp shade, showing my new design.

I claim:

The ornamental design for a lamp shade as shown.

ESTILL B. BROWN.

Witnesses:

F. M. EGAN,

H. C. TUXBURY.
